UNITED STATES PATENT OFFICE.

JOSEPH L. DOSTAL, OF DETROIT, MICHIGAN, ASSIGNOR TO EARL HOLLEY, OF DETROIT, MICHIGAN.

RISER FOR METAL MOLDS.

Application filed May 29, 1926. Serial No. 112,418.

The object of this invention is first to reduce the sprue loss when pouring metals into metal molds. Secondly, to give an indication to the man pouring a mold when he should cease to pour. Thirdly, to assist in washing out the cold shots which tend to float to the upper part of the casting.

Figure 1 shows a mold in elevation.

Figure 2 shows a cross sectional elevation 10 on the plane 2-2 of Figure 1.

In the figures, A is the sprue passage having a pouring mouth B. C is the riser opening into a cup D, in which the rising metal in C is easily visible. E is the end to the 15 sprue passage A, and F is the lateral gate leading therefrom feeding into the matrix G of the mold. This mold G is surrounded by a ring H, corresponding to the Phillips Patent #1,099,997, dated June 16th, 1914, 20 which bead may in its turn be provided with a groove J, as shown in my Patent #1,582, 169, dated April 27th, 1926.

Operation.—When the mold is poured, the molder filling the mold pours the iron into 25 the mouth B of the sprue A and watches the cup D connected to the riser C. The moment he observes iron entering C he ceases to pour. The level of the iron then in the sprue A and mouth B will stand momentarily at level corresponding to the broken lines 30 in C and E. Immediately the iron seeks its proper level. A small volume of iron is therefore caused to flow through F into the matrix G of the mold, after the molder has 35 ceased to pour. This quantity of iron is more or less constant, and it thus happens that a relatively constant quantity of iron passes into the matrix of the mold, and of

course a like quantity must at the same time pass out through the riser C at the termination of each pouring period.

Not only is this an advantage in that conditions are rendered more uniform, or rather it is made possible to make conditions uniform, but, what is of more importance, a 45 cold shot that might be formed beneath the riser C is carried off into C and a perfect casting thereby made.

If serious trouble with cold shots has to be eliminated, by continuing the pouring a 50 large quantity of molten iron is left in B, which results in a corresponding larger amount of iron flowing through C into D, and although the sprue loss will be greater the iron thus lost will perform a useful 55 function, namely the carrying away into D of cold shots which would otherwise form below C and spoil the casting.

What I claim is:—

In combination with a metal mold having 60 a matrix with an extensive surface and a restricted volume, a pouring mouth, a sprue having a volume comparable to that of the matrix, a gate leading therefrom and discharging into said matrix, a riser, a relatively 65 large cup into which the riser discharges at a level sufficiently far below the level of the entrance from the pouring mouth into the sprue that when the pouring operation ceases, iron will automatically flow down 70 the sprue and up into the riser cup, thereby displacing a considerable percentage of the iron from the matrix into the riser.

In testimony whereof I affix my signature.

JOSEPH L. DOSTAL.
